UNITED STATES PATENT OFFICE

2,627,790

BLADE PACKAGING MACHINE

Zemach Auerbach, New York, N. Y., assignor to
 The Gillette Company, a corporation of Delaware

Application August 26, 1948, Serial No. 46,352

18 Claims. (Cl. 93—1)

1

My invention relates to the art of packaging sharpened blades, such as razor blades, surgical instrument blades and the like. In particular the invention comprises a machine arranged successively to remove blades from a suitable magazine and introduce them into appropriately shaped slots previously cut through a strip of flexible paper, cardboard, or the like. The resulting package of blades is the subject matter of my co-pending applications Ser. No. 560,530 filed October 27, 1944; Serial No. 615,139 filed September 8, 1945; Ser. No. 783,948 filed November 4, 1937; and Serial No. 47,801 filed September 4, 1948.

The most important object of the present invention is to provide automatic mechanism for expeditiously and continuously forming packages of razor blades.

Another object of the invention is to increase the efficiency and reduce the cost of packaging keen blades.

Still another object of the invention is to provide automatic machinery capable of handling bare blades and assembling them into convenient package assemblies in such fashion that the blade edges are not impaired by being subjected to contact with any surfaces nor maneuvered in such a manner as to lead to the contamination of the blades by bacteria, germs, or the like.

An important feature of the invention resides in the combination of a blade magazine, strip feeding rolls, a punch operable to form a succession of slits or slots in the strip, and a carrier arranged successively to receive blades from the magazine and introduce them into the slots formed by the punch.

Another feature of the invention consists in an automatically actuated presser foot arranged to bear on the strip after the insertion of each blade in order to smooth the strip to conveniently flat form.

A further feature of the invention resides in the combination of two trains of mechanism driven from the same source and both operating on the feed rolls, one being operated first to advance the strip through a series of short steps separated by pauses, the other train then being actuated automatically to advance the strip a long step sufficient to separate groups of blades assembled on the strip as a continuous progression of packages.

These and other objects and features of the invention will be best understood and appreciated from the following detailed description of a preferred embodiment thereof selected for purposes of illustration and shown in the accompanying drawings, in which:

Before proceeding to a detailed description of the elements of the machine shown in the drawings I shall first outline the essential instrumentalities and their relationship. For this purpose I shall refer to Figs. 10 and 11 wherein

a strip 86 of paper, cardboard or the like is led first between a pair of feed rolls 78 and 80 and then vertically up to a second pair of feed rolls 96 and 98. A punch 184 is disposed on one side

of the strip and cooperates with a female die 189, the punch being actuated by a cam 166 mounted on a shaft 164. Spaced from the punch is a blade magazine 210 for holding a stack of centrally slotted, double-edged razor blades 212 shouldered at both ends as shown, for example, in Fig. 20. A carrier 216 reciprocates beneath the magazine through a long slot in a table 209, and the carrier has a lip 218 arranged to push the bottom blade 220 out of the magazine and toward the strip 86. The punch and die form a series of tongue-forming slots 190 in the paper

55

strip as shown in Fig. 20. The feed rolls being actuated first through a series of five short steps separated by pauses in the first of which the punch is actuated to form a slot, the strip is moved a step, and the carrier is moved to introduce one end of a blade in the slot formed by the punch during the preceding pause. At the end of the five short steps, another train of mechanism is actuated to advance the paper strip one long step as also shown in Fig. 20. Thus groups of blades are assembled on the continuous strip and can later be separated into individual packs of five (or any other desired number).

A finger 222 is automatically swung up through the center slots of the blades in the magazine prior to each advance of the carrier 216; as the carrier moves forward to remove the bottom blade it also swings the finger 222 which remains in the slot of the bottom blade to keep it straight during the first part of its movement toward the strip.

To make way for the blade 220 a cam 174 first pushes a receiver and guide 196 through the slot 190, its forward edge has a blade-receiving notch 200 which encounters the leading edge of the end of the blade 220. The further advance of the carrier 216 pushes the blade and the receiver forward until the end of the blade extends through the slot in the strip and the tongue 191 passes through the blade slot to lock the blade upon the strip 86.

In its forward movement the carrier 216 swings a presser foot 250 upwardly and forwardly through the slot of the blade 220 to bear against the tongue 191 and push it back into the plane of the strip where it is held in place by friction.

The carrier then retreats, leaving the blade locked on the strip, and the presser foot 250 is swung down out of the way. As the strip is then moved upwardly, the blade engages a projection and is turned through an arc until it lies substantially flat on the preceding blade.

With the foregoing outline established I shall now proceed to describe the specific elements of the machine shown in the drawings.

General organization

The machine, as best shown in Fig. 1, is mounted on a stout metal base plate 10 secured to a table or stand 11. Extending vertically from the base 10 is a pair of steel walls or frame members 12 and 14 running longitudinally along the base and disposed in spaced parallel relation. A long rectangular H-shaped casting 16 is secured to the base 10 adjacent one side. Jounaled in the walls 12 and 14 is a main drive shaft 18 carrying a pulley 20 for a V belt 21 driven by a suitable motor (not shown). Mounted on the shaft 18 is a broad pinion 22 which meshes with a large gear 24 fast upon a floating shaft 26 also jounaled in the walls 12 and 14 but capable of endwise movement through bearing housings 28 and 30 secured to the walls 12 and 14. At its inner end the shaft 26 carries a broad pinion 32 which meshes with a large gear 34 on the end of a cam shaft 36 also jounaled in the walls 12 and 14 and carrying a cam disk 38 having a lateral projection 40, the cam disk bearing continually upon a collar 42 secured to the face of the gear 24.

Although the shaft 26 with the gears 24 and 32 may move endwise, the shaft is continuously driven from the broad pinion 22 and continuous-

ly drives the cam shaft 36 through the broad pinion 32.

The long stroke train

A clutch member having a toothed hub 44 is secured on the shaft 26 in cooperative association with a matching clutch member 48 loosely mounted on the shaft 26, while a compression spring 46 disposed between the hubs of the clutch members urges them apart and also forces the collar 42 into constant engagement with the cam 38. When the cam projection 40 bears on the collar 42, the shaft 26 is displaced endwise until the hubs 44 and 48 are engaged. The clutch member 48 extends outwardly through the wall 12 and terminates in a sleeve 50 integral with an enlarged head 52 into which an eccentrically disposed crank pin 54 is threaded. A link or crank arm 56 pivotally mounted at one end on the eccentric pin 54 is secured at its other end to a pin 58 secured to the face of a large gear 60 mounted for rotation on a stud 62 secured to the wall 12. The gear 60 is engaged with a pinion 64 loosely mounted on the end of a shaft 66, and a pawl arm 68 is secured to the face of the pinion 64. A pawl 70 is carried on the end of the pawl arm 68 and engages a ratchet wheel 72 fixed to the shaft 66 journaled in the walls 12 and 14.

When the clutch hubs 44 and 48 are forced into engagement by the cam 40, the sleeve 50 turns and causes the crank arm 56 to reciprocate and rock the gear 60 back and forth. In so doing the pinion 64 rocks the pawl arm and causes the pawl 70 to engage the ratchet 72 and step it along. When the cam projection 40 passes by the collar 42, the clutch hubs disengage and the train of mechanism stops.

The shaft 66 enters a coupling member 74 accommodating a shaft 76 journaled in the casting 16. As best shown in Fig. 7, the shaft 76 carries a feed roll 78 disposed within the casting 16 and bearing upon a complementary idler feed roll 80 fast upon a pin 81 journaled at each end in bearing blocks 82 working in slots cut in the sides of the casting 16 and urged toward the feed roll 78 by compression springs 84.

A continuous strip 86 of paper cardboard or the like is drawn from a reel 83 secured to the stand 11 and led through the bite of the rolls 78 and 80. A gear 85 on the end of the shaft 76 meshes with a large gear 88 mounted on a stud 90 secured to the casting 16 above the shaft 76. The gear 88 meshes in turn with a small gear 92 secured on the end of stub shaft 94 journaled in the top of the casting 16 and carrying an upper feed roll 96 disposed directly above the roll 78. An idler feed 98 is mounted on a pin 99 mounted at each end in bearing blocks 100 working in slots cut in the casing 16 and urged toward the feed roll 96 by compression spring 102. The strip 86 is thus led vertically upward from the lower feed rolls 78 and 80 to the upper feed rolls 96 and 98, all four feed rolls being driven in unison through the gear train described.

When the clutch members 44 and 48 are engaged, the pawl 70 acts on the ratchet to step the shafts 66 and 76 along, thus turning all four feed rolls to advance the strip 86 a predetermined distance corresponding to the spacing desired between adjacent blade package groups on the strip 86, as shown best in Fig. 20.

The short stroke feed train

To feed the strip 86 through the nine short steps necessary for the punching and introduc-

tion of the five blades of a single package, I provide a train of mechanism beginning with the floating shaft 26. On this shaft is mounted a clutch hub 110 normally engaging a complementary clutch member 112 loosely mounted on the shaft 26 and integral with a sleeve 116 extending through the wall 14 and the bearing housing 30 to terminate in an eccentric surrounded by a collar 118 integral with one end of an eccentric link 120. The other end of the eccentric link 120 is pivotally secured to a pin 124 carried by a pawl arm 122 loosely mounted on the shaft 66 and carrying a pawl 126 engaged with a ratchet wheel 128 fast upon the shaft 66. On the base 10 is mounted a back-last-preventing pawl 130 urged upon the ratchet wheel by a spring 132, all as shown in Fig. 8.

When the shaft 26 turns and the clutch members 110 and 112 are engaged, the eccentric link 120 is reciprocated to cause the pawl 126 to step the ratchet wheel 128 and thus turn the shaft 66 to operate the four feed rolls in the same manner as previously described. The gear ratios and the cam 38 are so designed that the crank 120 moves the feed rolls through five short steps each time the clutch is engaged. When the cam projection 40 displaces the shaft 26, the clutch members 110 and 112 are disengaged and the long stroke mechanism is engaged. The two ratchet wheels 72 and 126 operate to turn the same shafts but do not interfere with one another. If it be desired to pack blades in groups other than fives, the short stroke feed train is set to advance the strip n steps, " n " being the number of blades in a group.

The punch drive

For reciprocating the punch 184 I provide a train beginning with the clutch member 112, which is secured to a gear 114 also loosely mounted in the shaft 26 and meshing with a gear 150 mounted for rotation upon a stud 152 set in the wall 14. Meshed with the gear 150 is a gear 154 also mounted on a stud 156 set in the wall 14. The gear train terminates in a gear 158 fast upon a shaft 160 journaled in the walls 12 and 14 and entering a coupling 162 by means of which the shaft 160 is coupled to a cam shaft 164 journaled in the casting 16 above the feed roll 78. As best shown in Fig. 17 the shaft 164 carries a cam 166 within the casting 16 and a pinion 168 at its outer end. The pinion 168 meshes with a pinion 170 fast on the grid of a stub shaft 172 journaled in the casting 16 directly above the shaft 164 and carrying a cam 174. Within the casting 16 between the cam shafts 164 and 172 and the strip 86 is a block 176 having an enlarged cubical base 178 through which two slots 180 and 182 are cut to receive a punch or male die member 184 and a blade guide 196.

The punch 184, as shown best in Fig. 22, includes a curved head 186 bearing on the cam 166, a shank, and a cutting edge 188 shaped to cut a slot 190 (Fig. 20) through the strip 86. The slot is twice offset to produce a tab or tongue 191. Secured to the base 178 opposite the punch 184 is a female die 189 shaped to receive the die 184.

The blade guide and receiver 196 is rounded at its rear end and bears on the cam 174. In Figs. 4-6 the details of the blade guide are shown. The rear end 198 is reduced in thickness, the center portion is broad and flat, and the front end has secured to its lower face a strip 199 cut to form a notch 200 in conjunction with the upper member 196, the front edge of which is ap-

propriately bevelled to combine in the formation of the blade receiving notch 200.

When the clutch 110-112 is engaged, the gear 114 is rotated to drive the shafts 160 and 164 through the gears 150, 154, and 158. The cam shafts 164 and 172 then turn to cause the cams 166 and 174 to push first the punch 184 and then the blade guide 196 through the block 176 and through the strip 86. The punch 184 is urged toward the cam 166 by means of a compression spring 194 housed in the base 178 and bearing on the depending flange of the punch head 186. It is to be understood that after the punch has been actuated, the short stroke feeder advances the strip 86 one short step until the slot formed by the punch is moved upwardly in line with the blade guide 196 which then enters the slot and pushes the tongue 191 outwardly at approximately right angles to the strip as best shown in Fig. 12.

The carrier

The casting 16 is provided with a top or table 209 having a central slot 214 leading to the blade guide 196 and serving as a guideway for a reciprocating carrier or pusher 216. Mounted on the table 209 over the slot 214 is a vertical blade magazine 210 arranged to hold a horizontal stack of bare, double-edged, centrally slotted razor blades 212. At its forward end the carrier 216 is provided with a slight projection or lip 218 just high enough to engage only the lowermost blade 220 in the magazine 210. A slim finger 222 is carried upon a pin 224 mounted for rotation in the side walls of the casting 16 and engaged by a tension spring 226 which urges the back of the finger against the front end of the carrier 216. The finger extends upwardly through the slot 214 and through the center slots of the blades 212 in the magazine 210. As the carrier 216 moves forward pushing the lowermost blade 220 ahead of it, the finger 222 is pushed forward and down; this motion serves to move the blade 220 with the finger 222 until the blade is disengaged from the stack and well on its way. During this time the finger 222 preserves the alignment of the blade and prevents lateral shifting thereof.

At its rear end the carrier 216 is provided with an upright slotted standard 228 in which works a crank pin 230 set in the face of a disk 232 mounted on the end of a shaft 234 journaled in a bearing housing 236 secured on the casting 16. The shaft 234 enters a coupling 240 which serves to couple in a shaft 238 journaled in a bearing housing 242 secured on the wall 14. On the end of the shaft 238 is a gear 244 meshing with the gear 114 which, as previously described, is driven through the clutch 110-112 on the shaft 26.

Rotation of the gear 244 takes place only when the clutch is engaged, the carrier train thus being associated with the cam shaft drive and the short step feed train. When the clutch 110-112 is disengaged and the clutch 44-48 is engaged, the long stroke feed train operates by itself, the rest of the mechanism remaining stationary.

The carrier 216 pushes the blade 220 forwardly into the notch 200 of the blade guide 196 then extending through the slot in the strip and also pushes back the blade guide. The machine is so timed that the carrier then starts back. The cycle of the carrier, punch, and blade guide is shown progressively in Fig. 18 (retracted), Fig. 11 (starting forward), Fig. 12 (halfway along), Fig. 13 (blade engages blade guide), and Fig. 14

(blade introduced end foremost into the strip 86, punch actuated).

The presser foot

In order to return the tongue 191 to a position flush with the strip 86 after the introduction of the blade, I provide a pivoting presser foot 250 working on a pivot pin 252 set in a block secured to the bottom of the table 209 in such position that the presser foot 250 works in the slot 214. The presser foot is longitudinally slotted to receive an actuating pin 258 carried by a rod or bolt 260 slidably mounted in the block 254 and containing a compression spring 266 tending to force the bolt to the rear and to carry the presser foot back and down. The rear end of the bolt 260 has an enlarged head 262 cut away along one side as shown at 264. Cooperating with the bolt 260 is a latch 268 pivotally secured to the block 254 and urged by a spring 272 to rock to a position bearing on the bolt 260 beneath its head 262. The bolt head 262 intercepts the carrier 216 which forces the bolt forwardly as it moves ahead. In so doing the presser foot is pivoted upwardly through the slot in the blade 220. Finally the presser foot 250 carries the tongue 191 back into the plane of the strip 86 after the end of the blade has passed into its prepared slot. The latch 268 is sprung in behind the bolt head 262, at the end of the forward stroke of the latter to restrain the bolt from rearward movement when the carrier withdraws.

A rod 274 having a blunt point is carried in guide lugs 275 mounted on the bottom of the table 209. The rod 274 is urged rearwardly by a compression spring 276 bearing on the forward guide 275 and a collar 278 pinned to the rod 274. Pivotally mounted on the rear guide 275 is a trigger 280 bearing at its lower end on the end of the rod 274 and having its upper end lying in the path of the carrier 216. The blunt point at the forward end of the rod 274 is disposed adjacent the lower end of the pivoting latch 268. When the carrier returns to its rearmost position, it swings the trigger 280 which pushes the rod 274 forward against the spring 276. The pointed forward end of the rod then engages the latch 268 and rotates it until it disengages the bolt head 262. Thereupon the spring 266 forces the bolt 260 rearwardly, while the pin 258 pulls the presser foot back and down from the position shown in Fig. 14 to that shown in Fig. 10.

Fastened to the magazine 210 is an inclined plate 290 which leads to the bite of the upper feed rolls 96 and 98. After a blade has been introduced into a slot in the strip 86 and the carrier and presser foot have returned to rest position, the feed train operates to move the strip upwardly. In so doing the end of the blade 220 which extends through the slot meets the corner of the slot 180 and begins to turn through a ninety degree arc until it lies substantially flat on the preceding blade. As the strip 86 then proceeds further upward the free end of the blade engages the plate 290 which converges toward the strip and gradually completes the turn of the blade until it is flat enough to pass through the bite of the upper feed rolls.

The complete cycle of the machine may, for convenience, be regarded as beginning in the center of the long feed stroke. At this time the clutch 44-48 is engaged and the clutch 110-112 disengaged. Consequently the carrier 216, punch 184, blade guide 196, and short stroke feed mechanism all are stopped. The long stroke mecha-

nism operates until the cam 40 disengages the clutch 44-48. The strip 86 pauses, and the clutch 110-112 engages. The punch 184 is just actuated to form a slot in the strip 86, but the

5 short stroke feeder operates to move the strip before the carrier 216 or blade guide 196 can be actuated. Then there is a pause in the feed during which the carrier 216 and blade guide 196 operate with the presser foot 250 to insert a 10 blade in the slot formed by the punch during the first pause. The punch also operates during the second pause. This sequence is repeated until the sixth pause (which follows the fifth short stroke), in which the cam 40 disengages the 15 clutch 110-112, the timing being so adjusted that the fifth blade is inserted in the fifth slot but the trains of mechanism are stopped before the punch is actuated to form what would be a sixth slot. Thereupon the clutch 44-48 is engaged 20 to place the long stroke mechanism in action, and the cycle has begun again.

Having thus disclosed my invention and described in detail an illustrative embodiment thereof, I claim as new and desire to secure by

25 Letters Patent:

1. A blade packaging machine comprising a blade magazine, feed rolls arranged to feed a flexible unperforated strip along a path spaced from said magazine, means for operating said feed rolls through a series of short steps separated by pauses, a punch movable to cut a slot in the strip during the pause after each feed step, a carrier arranged to remove a blade from the magazine and insert it end foremost through a 30 slot formed by said punch in a position beyond that in which the slot is formed by the punch, and a common power-operated mechanism for actuating both the punch and the carrier.

2. The machine defined in claim 1 wherein the carrier inserts the blade in the slot during the pause between the feeding strips following that in which the said slot was formed.

3. A blade packaging machine comprising a blade magazine, feed rolls arranged to feed a flexible strip along a path spaced from said magazine, automatic feed roll driving mechanism including separate pawl and ratchet elements arranged first to move the strip through a series of short steps separated by pauses and then 45 through one long step, a punch, means for automatically moving the punch through the strip during each of said pauses, a carrier movable to remove a blade from said magazine and insert it in a hole made by said punch, and a common power-operated mechanism for actuating both the automatic punch moving means and the carrier.

4. A blade packaging machine comprising a blade magazine, feed rolls arranged to feed a flexible strip along a path at one side of said magazine, automatic feed roll driving mechanism including separate pawl and ratchet elements arranged first to move the strip through a series of short steps separated by pauses and then 50 through one long step, a punch, means for automatically moving the punch through the strip during each of said pauses, a carrier movable successively to remove blades from the bottom of the magazine and insert them in holes formed by said punch, each blade being inserted during the pause following that during which the punch formed the corresponding hole, and a common power-operated mechanism for actuating the automatic punch moving means and the carrier.

5. A blade packaging machine comprising a

blade magazine, feed rolls arranged to feed a flexible strip through a path spaced from said magazine, feed roll driving mechanism including means for feeding the strip through a series of short steps separated by pauses and means for feeding the strip one long step after each series of short steps, a cam controlled clutch for automatically operating the short step feeder and then the long step feeder, a punch movable to form a slot in the strip, punch driving means controlled by said clutch for actuating the punch once during each of said pauses, and a carrier also controlled by said clutch for removing successive blades from the magazine and introducing them into the slots formed by said punch.

6. A blade packaging machine comprising a magazine for centrally slotted blades, feed rolls arranged to feed a flexible strip along a path at one side of said magazine, a punch arranged to form tongues and associated slots in said strip, a carrier arranged to remove blades successively from the magazine and introduce them into the slots formed by said punch, a presser member, and means for moving said presser member through successive blade slots to press each tongue toward the plane of the strip after the blade has been introduced into the slot.

7. A blade packaging machine comprising intermittently acting strip feeding mechanism, a punch synchronized with the feeding mechanism and shaped to cut tongued slots one by one in spaced series in a strip, means for inserting in each slot the end of a slotted blade, and means for folding a tongue over the end of each successive blade as it is inserted in the strip.

8. A blade packaging machine comprising a magazine for blades, feed rolls arranged to feed a strip along a path spaced from said magazine, a carrier movable to remove blades from said magazine and carry them toward the strip to be reciprocated through a path intersecting the strip, a blade guide movable through a path intersecting the strip and meeting said carrier means for first advancing the strip through a relatively long step and then through a plurality of short steps, and means for first actuating the punch and then simultaneously actuating the carrier and blade guide.

9. A blade packaging machine comprising means for intermittently advancing a strip along a straight path, a punch movable through a path intersecting the strip path, a blade carrier movable to present a blade end foremost to the strip in a path disposed at right angles to the strip path at a point remote from the point of intersection of the strip path and the path of the punch, and common power-operated mechanism for automatically actuating the punch and the carrier in sequence.

10. A blade packaging machine comprising a blade magazine, feed rolls for advancing a flexible strip along a path adjacent said magazine, a blade carrier movable between the magazine and the strip, a punch movable to and from the strip, a first clutch, means driven through said first clutch for actuating the feed rolls, carrier and punch, a second clutch, means driven through said second clutch for actuating the feed rolls, and means for selectively engaging said clutches.

11. A blade packaging machine comprising a plurality of cooperating feed rolls for advancing a flexible packaging strip, a shaft controlling the movement of said rolls, a pair of ratchet wheels secured to said shaft, independent trains of mech-

anism for rotating said ratchet wheels to different degrees, a clutch controlling each train, and means driven through one of said clutches for punching said strip and inserting a blade therein while the feed rolls remain at rest.

12. A blade packaging machine comprising a plurality of cooperating feed rolls for advancing a flexible strip, a shaft controlling the movement of the feed rolls, separate trains of mechanism for rotating said shaft, a clutch controlling each of said trains, a blade carrier, means for reciprocating said carrier, a punch, means for reciprocating said punch, the reciprocating means for the carrier and punch being driven through one of said clutches, and a cam arranged first to engage one clutch and simultaneously disengage the other whereby the feed rolls, carrier, and punch are simultaneously operated, said cam then reversing the clutches so that the feed rolls alone are operated.

13. A blade packaging machine comprising a magazine for blades, a plurality of feed rolls cooperating to advance a flexible strip along a path adjacent the blade magazine, a carrier movable to carry a blade from the magazine to the strip, a punch movable to punch tongue-defining slots in the strip, a blade guide movable to elevate a tongue and guide a blade into the strip from the carrier, and a presser foot movable to depress the tongue elevated by the blade guide.

14. A blade packaging machine comprising a magazine for blades, means for advancing a flexible strip past the magazine in a series of steps, a carrier movable to remove a blade from the magazine and carry it to the strip, a punch actuated intermittently to form slots in the strip, means for driving the punch and the carrier, a clutch controlling the driving means, and a cam for disengaging said clutch after a predetermined number of operations of the punch and carrier.

15. A blade packaging machine comprising a magazine for shouldered blades, a reciprocating punch, feeding mechanism for intermittently advancing a packaging strip across the path of the punch for forming a predetermined number of short slits therein in cooperation with the punch, a reciprocating carrier movable at right angles to the strip to insert a blade end foremost in each slit until the shoulders of the blade engage the strip at both ends of a slit and a common power-operated mechanism for actuating the punch and carrier.

16. A blade packaging machine comprising a blade magazine, means for feeding a flexible packaging strip along a path spaced from said magazine, a punch movable to cut successive slots in said strip, a carrier movable in a path at right angles to the slotted strip arranged to remove a blade from the magazine and insert it end foremost through each slot after the punch has been retracted from the strip, and a common power operated mechanism for both moving the punch and operating the carrier.

17. A blade packaging machine comprising a blade magazine, means for feeding a flexible packaging strip along a path at one side of said magazine, a punch movable to cut successive slots in said strip, a reciprocating carrier movable in a path at right angles to the slotted strip arranged to remove a blade from a magazine and insert it end foremost through each slot after the punch has been retracted from the strip, and a common power operated mechanism for moving

11

the punch and reciprocating the carrier in timed relation.

18. A blade packaging machine comprising a blade magazine, means for feeding a packaging strip intermittently along a straight path, means for slotting the strip while at rest in said path, a blade carrier movable from the magazine at right angles toward the slotted strip, a blade guide movable through the slotted strip to meet a blade presented end-foremost by the carrier and then to retreat through the strip thereby guiding the end of the blade through the slot.
